CONTROL SYSTEM FOR DUAL FIRING RATE
OIL BURNERS

Richard M. Cochrane, Longmeadow, Mass., assignor to Gilbert & Barker Manufacturing Company, West Springfield, Mass., a corporation of Massachusetts

Application March 5, 1948, Serial No. 13,138

3 Claims. (Cl. 236—9)

1

This invention relates to improvements in control systems for dual firing rate burners, more particularly such burners as may be used in the heating equipment for houses for heating the rooms of the house and for heating water for the hot water supply system for the house.

The invention, in one important aspect, relates to controlling a burner, which has one firing rate for heating the rooms of a house and another firing rate for heating water for the hot water supply system.

The invention is closely related to a prior invention of Logan and Bills, disclosed in their pending application Serial No. 8,184, filed February 13, 1948, now Patent No. 2,464,697, dated March 15, 1949, in that the invention, herein to be disclosed in the particular aspect above mentioned, is an improvement on that of said application, although in other aspects, it is independent. The disclosure of the present invention is, however, made without depending on said prior application to fully point out herein the utility of this invention in all its aspects. The scope of this invention will be distinctly pointed out in the appended claims.

Among the purposes of the present invention are (1) to provide a way for a room thermostat to dominate a hot water thermostat so that an oil burner can be operated at a high firing rate for the purpose of room heating, whenever the room thermostat calls for heat, regardless of whether the hot water thermostat is or is not calling for the operation of the burner for the purpose of heating hot water, and, in addition, to operate the burner at a low firing rate, whenever the hot water thermostat operates to effectively call for operation of the burner for the purpose of heating hot water; (2) to provide a way for the burner, when used for firing a steam or hot water boiler, to always start up at the high firing rate, whenever the room thermostat calls for heat, and operate at such rate until the mains are filled with steam or hot water, as the case may be, and then operate at a low firing rate, if the weather is relatively mild, or at a high firing rate, if the weather is severe, as may be determined by a firing rate selector, which may be set manually or automatically for the firing rate needed; and (3) to provide in an oil burner, which has two nozzles, one with a high and the other with a low firing rate, and in which one or the other of these nozzles is selected for operation by a selector device—a way for operating the unselected nozzle briefly at the end of each run of the burner to purge it of hot oil.

2

The invention will be disclosed with reference to the accompanying drawings in which—

- Fig. 1 is a top plan view of one form of burner with which the control system may be used;
5. Fig. 2 is a diagrammatical view illustrative of the oil supply connections and controls and the air supply connections and controls;
- Fig. 3 is a diagrammatical view of a control system embodying the invention;
10. Fig. 4 is a view, similar to Fig. 2, but showing alternative controls for the oil and air supply;
- Fig. 5 is a diagrammatical view showing the control system adapted for use with the oil and air supply controls of Fig. 4;
15. Fig. 6 is a diagrammatical view of the control system as used when the nozzle purging feature of Fig. 3 is not desired;
- Fig. 7 is a fragmentary diagrammatical view showing the change necessary in the Fig. 3 control system when the feature of always operating the burner initially at the high firing rate, is not desired; and
20. Fig. 8 is another fragmentary diagrammatical view, showing the change necessary in the Fig. 6 control system when the selector switch and surface thermostat switch of Fig. 6 are omitted.
25. Referring to these drawings; there is shown in Figs. 1 and 2 an example of one kind of oil burner, with which the control system of this invention may be used to advantage. The system is, however, capable of use with other kinds of burners and is not to be limited to use with the single form of burner herein disclosed as one illustrative example.
30. There is shown in Fig. 1, a burner of the so-called gun type, wherein air is supplied by a fan 1, located in a housing 2, to an air conduit 3, having an open end 4, adapted to be inserted into the fire box of a suitable heating apparatus, such as a steam boiler, hot water boiler, or hot air furnace, for example. The rear end of conduit 3 is closed. The fan 1 is driven by direct connection to the shaft 5 of an electric motor 6, fastened to one side of the fan housing 2.
35. The burner also includes two atomizing nozzles 7 and 8, which are adapted for connection one at a time to an oil supply pump 9 in a manner later to be described. As shown, both nozzles are located in the one air conduit 3, near the outlet end thereof. However, in some cases, the nozzles may be located in separate air conduits, both supplied by the same fan, and the control system of this invention will be useful with such an arrangement. Preferably, each nozzle is of the oil pressure atomizing type and adapted to produce
- 40.
- 45.
- 50.
- 55.

a substantially conical fog-like spray of oil to mix with the air supplied by the fan. The air and oil mixture, thus produced, will be suitably ignited, as by a pair of spark electrodes 10. The nozzles 7 and 8 preferably have different capacities. As a single illustrative example, the nozzle 7 may have a capacity of one gallon per hour and the nozzle 8 may have a capacity of one and one half gallons an hour, both at a pressure of say 100 pounds per square inch.

The oil pump 9 is fixed as indicated to the cross bar portion 11 of a yoke, the legs 12 of which are integrally connected to the fan housing 2. This pump is driven by the motor 6, preferably through the intermediary of a speed-responsive clutch, the driving and driven elements of which are respectively indicated at 13 and 14. As shown, the shaft 15 of the pump is connected to the driven element 14 of the clutch and the driving element 13 of the clutch is connected by a shaft 16 and a flexible coupling 17 to the hub of fan 1. The clutch arrangement is substantially like that shown in the Logan Patent No. 1,985,934, granted January 1, 1935, and enables the motor and fan to acquire considerable speed before the oil pump is started and enables the pump to be stopped before the fan, for the purposes set forth fully in said patent.

The air inlet to the fanhousing 2 is shown at 18. It is controlled by an annular shutter 19, the central opening of which receives the clutch elements 13 and 14, as best shown in Fig. 2. The shutter is supported by a screw 20, on which it is threaded, and this screw has smooth cylindrical portions, one near each end thereof, which are slidably and rotatably mounted, one in a bearing 21 in housing 2 and the other in a bearing 22 in the cross bar 11. The screw 20 is bodily movable in the direction of its axis to carry the shutter 19 from a position suitable for high firing rate operation to a position suitable for low firing rate operation and vice versa. The screw has a shoulder 23 which is adapted to abut the adjacent end face of bearing 21 and limit the axially inward movement of the screw and thus define the low firing rate position of the shutter. Such position may be varied by rotating screw 20. Sliding movement of the screw in the opposite direction is limited by a second screw 24, with the inner end of which a circumferentially grooved collar 25, fixed to screw 20, is adapted to abut and determine the high firing rate position of the shutter. The screw 24 is threaded into a circular end housing 26, secured to the cross bar 11. By turning screw 24, the high firing rate position of the shutter may be adjusted. A part-cylindrical member 27 encloses the space between the member 26 and housing 2, except for suitable openings to enable air to enter and reach the inlet 18.

The air shutter 19 is shifted from one position to another by means of a lever 28, fulcrumed near its lower end at 29 and having its upper end engaged in the groove in collar 25. The lower end of this lever is pivotally connected to the outer end of a piston rod 30, the inner end of which carries a piston 31, slidably mounted in a cylinder 32. The inner end of this cylinder is closed and the piston is held in abutment with this closed end by means of a spring 33, coiled around rod 30 and acting between the outer face of piston 31 and a head 34, which is threaded into the outer end of the cylinder and slidably supports the piston rod. When the burner is not in operation, the shutter is held in high firing rate position by spring 33. When the burner is oper-

ating at the high firing rate, the shutter is held in the same manner and in the same and illustrated position. When the burner is to operate at the low firing rate, oil is admitted to the inner end of cylinder 32 and the piston 31 is moved outwardly, rocking lever 28 clockwise and bodily moving screw 20 until the shoulder 23 abuts the adjacent end face of bearing 21, thus carrying the shutter 19 into position for low firing rate operation and holding the shutter in such position.

The oil pump 9 includes a combined cut-off and pressure-regulating valve housed within the pump casing. This valve is shown diagrammatically by a piston 35, pressed by a spring 35' against a seat 36, through which the pump outlet passage 37 extends. Oil drawn into the pump from a suction pipe 38 is forced by the pump into a chamber 39 and, when the oil reaches a predetermined minimum pressure, say 85 pounds per square inch, the piston 35 is moved to the left away from seat 36, allowing oil to enter the outlet 37 and flow to one or the other of the nozzles 7 and 8 in a manner later to be described. When the oil in chamber 39 reaches a maximum predetermined pressure, say 100 pounds per square inch, piston 35 will be moved to the left far enough to uncover a port 40 and allow oil from chamber 39 to flow through port 40 into a chamber 41 which is connected to the suction side of the pump. An example of one pump suitable for the purpose will be found in Wahlmark Patent No. 2,232,983, dated February 25, 1941, to which reference is made for a complete disclosure of the pump structure with its cut-off and pressure-regulating or by pass valves, if necessary or desired.

The flow of oil from the pump to the nozzles 7 and 8 is respectively controlled by two valves 42 and 43. The valve 42 is of magnetic material and is located within a tube 44 having an inlet in its peripheral wall, which is connected to the outlet 37 of the oil pump by means to be later described and having two outlets, one in each end thereof. This tube is made of non-magnetic material. The valve 42 is normally held by means of a spring 44' in the illustrated position against a seat 46 to close the outlet to a pipe 47, which extends to nozzle 7. A solenoid 48 surrounds tube 44 and is arranged in a casing 45 of magnetic material. When solenoid 48 is energized, it lifts valve 42 until it engages a seat 49 in the upper part of casing 45 and closes an outlet, which is connected to a pipe 50, leading to the suction side of pump 9, as to pipe 38. The valve 43 is also made of magnetic material and is located in a tube 51 of non-magnetic material, having an inlet connected by a pipe 61 to the outlet 37 of the oil pump, and two outlets 53 and 57, one in each end thereof. Valve 43 is held by a spring 52 against a seat 53 to close an outlet, which is connected by a pipe 54 to nozzle 8. A solenoid 55 surrounds tube 51 and is located in a magnetic casing 56. When the solenoid 55 is energized, it raises valve 43, allowing oil to flow through pipe 54 to nozzle 8, and moves it against a seat 57 to close an outlet which is connected to a pipe 58. Pipe 58 has a branch 59 leading to the inner end of cylinder 32 and a branch 60 leading to the described inlet of tube 44 of valve 42. When valve 43 is positioned as shown, the inlet of tube 44 is connected to the outlet 37 of the oil pump by means of pipes 60 and 58, tube 51 and pipe 61.

The solenoid valves have been shown merely in diagrammatical form. These valves per se are standard commercial articles, which can be bought in the market, and complete illustration

and description of them is therefore deemed unnecessary.

When the low rate nozzle 7 is to be operated, the solenoid 48 is energized and the solenoid 55 remains deenergized. The valve 42 is raised to engage seat 49, while the valve 43 remains, as illustrated, engaged with seat 53. The pump 9 will force oil through pipe 61 into tube 51 and thence through pipes 58 and 60 into tube 44 and thence through pipe 47 to nozzle 7. The raised valve 42 closes the outlet to pipe 58 and thus disconnects the cylinder 32 from the suction of pump 9. Oil from the pump, flowing into pipe 58 as described, will also flow through pipe 59 into the inner end of cylinder 32 and move piston 31 outwardly to shift the shutter 19 into low firing rate position. The closed valve 43 prevents oil from flowing to the high rate nozzle 8.

When high firing rate operation is desired, the solenoid 55 is energized and the solenoid 48 remains deenergized. Accordingly valve 43 is raised to engage seat 57 and valve 42 remains engaged with seat 46 as illustrated. Oil from pump 9 will then flow through pipe 61 into tube 51 and from the latter through pipe 54 to the high rate nozzle 8. Oil cannot pass to the cylinder 32 or tube 44 because the valve 43 engages seat 57. The lowered valve 42 closes the outlet to the nozzle 7 and enables cylinder 32 to communicate with the suction side of pump 9 by way of pipes 59 and 60, tube 44, and pipes 50 and 38. Accordingly, the piston will be moved to the illustrated position for high rate firing.

As is usual in burners of this kind (Fig. 3), the motor 6 and the primary 62 of an ignition transformer are connected in parallel in a burner operating circuit, which is controlled by a switch 63, operated by a relay or electromagnet 64, under the control of a suitable thermostat switch. This relay switch is part of a main control instrument, which is located within the dot-dash line in Fig. 3 and has terminals 65 and 66, adapted to be connected to the wires 67 and 68, of a suitable supply source, usually 115 volts A. C., and a terminal 69, which is connected by a wire 70 to one terminal of the motor 6 and to one terminal of primary 62. The other terminals of the motor and primary are connected by a wire 71 to terminal 66. A wire 72 connects terminal 65 to the contact of switch 63 and the blade of the latter is connected by a wire 73 to terminal 69. A limit switch 74, such as a steam-pressure-actuated switch, for example, may be included in series in the supply wire 67, if desired. The secondary 75 of the ignition transformer is connected by wires 76 to the spark electrodes 10. When the electromagnet 64 is energized, switch 63 will close the burner operating circuit, comprising terminal 65, wire 72, switch 63, wire 73, terminal 69, wire 70, motor 6 and primary 62, wire 71 and terminal 66. The motor 6 will be started to supply air and oil for combustion and the ignition transformer will be energized to supply ignition sparks between the electrodes 10. When the electromagnet 64 is deenergized, the switch 63 will open to stop the motor and deenergize the ignition transformer.

The main control instrument also includes a step down transformer having a primary 77, which is connected by wires 78 and 79 to terminals 65 and 66, respectively, and a secondary 80, which supplies low voltage for the control circuits for the electromagnet 64. The low voltage circuits are shown by light lines to distinguish them from the high voltage circuits which are shown by heavy lines. The electromagnet usually also

actuates three switches 81, 82 and 83 besides the burner control switch 63. The blades of these last three switches are interconnected by a conductor 84. All these three switches are closed, when the electromagnet 64 is energized, and they are all open, when the electromagnet is deenergized. There is also provided a heat-actuated safety switch 85, which when heated by an electric heating coil 86 for a predetermined time, say for example 90 seconds, will open and remain open until manually reset. This sort of switch is well known per se in control circuits and is only diagrammatically indicated here. The main control instrument also includes a thermostat responsive to combustion temperature, such as a stack thermostat, conventionally shown at 87, which actuates several pairs of contacts 88, 89 and 90. One of the pair of contacts 88 is connected to one of the pair of contacts 89 as indicated. When cold, the thermostat 87 holds the pairs of contacts 88 and 89 engaged and the pair of contacts 90 separated as shown. On occurrence of combustion, the contacts 90 are first engaged, followed by the separation of the contacts 89 and then the separation of the contacts 88. On a subsequent failure of combustion, the contacts 90 will separate almost immediately and, in substantially two minutes, the contacts 89 and 88 will reengage.

One terminal of secondary 80 is connected by a wire 91 to one terminal of safety switch 85 and the other terminal of the latter is connected by wires 92 and 92' to one terminal of the relay coil 64. The other terminal of the latter is connected by a wire 93 to one terminal of heater coil 86 and the other terminal of the latter is connected by a wire 94 to one of the contacts 88. The other contact 88 and that one of the contacts 89, fixed thereto, are connected by a wire 95 to one of the contacts 90 and the latter is connected by a wire 96 to the contact of switch 81. The other contact 90 is connected by a wire 97 to wire 93. The other contact 89 is connected to a wire 98 which connects with a wire 99 extending to the contact of switch 82 and to a wire 100 extending to the blade of a switch 101, having two contacts 102 and 103. The contact 102 is connected by a wire 104 to a terminal 105 of the main control instrument. The contact of the switch 83 is connected by a wire 106 to one terminal of an electric heating coil 107 and the other terminal of the latter is connected by a wire 108 to the blade of a switch 109 having two contacts 110 and 111. The contact 110 is connected by a wire 112 to one terminal of a resistor 113 and the other terminal of the latter is connected by a wire 114 to a terminal 115. The secondary 80 has its right hand terminal connected by a wire 116 to a terminal 117. The contact 103 is connected by a wire 118 to a wire 119 and by the latter to a terminal 120. The contact 111 is connected by a wire 121 to a terminal 122.

The terminals 105, 115, 117, 120 and 122 of the control instrument are adapted to be connected to two thermostat switches one or the other of which starts the burner motor 6 on a demand for heat and stops the motor when such demand is satisfied. One thermostat switch comprises a bimetallic thermostat blade 123, which is responsive to the temperature of the water in the boiler and is used to control the burner for heating hot water, as for example, by an indirect heater through which the boiler water is circulated. This switch has contacts 124 and 125 which are adapted to be successively engaged in the order named by blade 123, when the temperature of the water in

the boiler falls below a predetermined value, and to be successively disengaged in the reverse order, when the temperature of the boiler water exceeds a predetermined value. The contacts 124 and 125 are respectively connected by wires 126 and 127 to terminals 117 and 105. The blade 123 is connected by a wire 128 to terminal 116. The other thermostat switch, commonly called a room thermostat, comprises a bi-metallic blade 129, responsive to the temperature in the space to be heated by the burner. This thermostat switch has two contacts 130 and 131, adapted to be successively engaged in the order named by blade 129 on a demand for heat and to be disengaged by the blade in the reverse order, when the demand is satisfied. These contacts 130 and 131 are respectively connected by wires 132 and 133 to terminals 117 and 120. The blade 129 is connected by a wire 131' to one terminal of a heating coil 132' and the other terminal of the latter being connected by a wire 133' to terminal 122. The coil 132' is adapted at certain times to heat the blade 129 and accelerate its disengagement from contact 130 as will later appear.

While it has been common, heretofore, to control the one burner by a room thermostat and by a hot water thermostat, the control system of this invention provides for the domination of the hot water thermostat by the room thermostat. If, for example, the burner is operating, under the control of the hot water thermostat 123, for the purpose of heating hot water and there is a demand for room heating, which causes the room thermostat 129 to close, the hot water thermostat will be disconnected from the burner control circuit and the room thermostat will be connected into such circuit in place of the hot water thermostat. This result is effected by the switches 101 and 109, which are actuated by an electromagnet 134, being moved by this electromagnet, when energized, from their respective right hand contacts 102 and 110 to their respective left hand contacts 103 and 111. The electromagnet 134 is connected at one end to the wire 92 and its other end is connected by a wire 135 to the wire 119.

On a demand for hot water heating, the hot water thermostat switch blade 123 will first engage contact 124 and shortly after engage contact 125. When both these contacts are engaged by the blade, a starting circuit will be closed to the relay 64 for closing switch 63 and operating the burner motor and ignition means. This circuit may be traced as follows—from the right hand terminal of secondary 80, by wire 116, terminal 117, wire 126, contact 124, blade 123, contact 125, wire 127, terminal 105, wire 104, contact 102, switch 101, wires 100 and 98, engaged pairs of contacts 89 and 88, wire 94, heating coil 86, wire 93, relay coil 64, and wires 92' and 92, switch 85 and wire 91 to the left hand terminal of secondary 80. The relay coil 64, being energized, the switch 63 closes to start the motor and ignition means and at the same time, the switches 81, 82 and 83 also close.

The switches 81 and 82, when closed, prepare an alternate or running circuit which is completed, when combustion occurs, by the action of the stack thermostat 81. Very soon after combustion occurs, the contacts 90 will engage and complete this running circuit by shunting out the heating coil 86 of the safety switch 85. This running circuit is the same as the starting circuit through the wire 100 and then extends by wire 99, closed switch 82, conductor 84, closed switch 81, wire 98, the contacts 90, which are then engaged, wire 97 to wire 93, down wire 93 to the relay coil 84 and

7
thence as heretofore described. The heating coil 86 is thus put out of action to prevent the safety switch 85 from opening. In about two minutes following the start of combustion, the contacts 89 open, followed shortly by the openings of contacts 88. If combustion does not occur within say 90 seconds after the relay coil 64 was energized, the safety thermostat switch 85 will be opened by the heat received from coil 86 and the burner will stop and can be started up again, only after switch 85 has been manually reset. If combustion initially occurs and there is a later failure while the motor 6 is operating, the burner will be stopped almost instantly by the opening of contacts 90. Then, after a scavenging period of about two minutes, the pairs of contacts 88 and 89 will reengage and establish the starting circuit, above described, whereby the burner motor will automatically be started. If combustion then occurs, the running circuit will be established, as above described. If combustion does not occur within 90 seconds, the safety switch 85 will open and stop the burner until the switch is manually reset.

When the demand for heat is nearly satisfied, 25 the blade 123 will have moved to the right far enough to disengage from contact 125 but not from contact 124. This does not stop the burner because of an alternate branch, which was established, when switch 83 closed. This branch extends from blade 123 by wire 128, terminal 115, wire 114, resistor 113, wire 112, contact 110, switch 109, wire 108, heating coil 107, wire 106, closed switch 83, and conductor 84, to closed switch 81. Previous to the separation of blade 123 from contact 125, no current flowed in this branch because of its relatively high resistance, due to the coil 107 and resistor 113 (if used), and the fact that the other branch, comprising contact 125, wire 121, terminal 105, wire 104, contact 102, switch 101, wires 100 and 99 and closed switch 82, has relatively low resistance. Thus the heating coil 107 can be energized only during the last few moments of each run of the burner and this is made use of for a purpose later to be described.

30 40 45 50 55 60 65 70 75
When the demand for heat is satisfied, the blade 123 leaves contact 124 breaking the circuit to relay coil 64, and causing switch 63 to open and stop the burner. The switches 81, 82 and 83 also open. Soon after combustion ceases, contacts 90 open breaking the running circuit in another place so that if the thermostat switch 123 should close, the burner could not be immediately started. The starting of the burner will be postponed until the combustion chamber has cooled enough to allow safe starting because of the delay of about two minutes, which is necessary for the stack thermostat 81 to cool enough to engage the contacts 88 and 89. When these contacts reengage the above described starting circuit will be re-established.

The operation of the control, as thus far described, is the usual one. A novel arrangement, now to be described, enables the room thermostat to dominate the hot water thermostat. Assume for example that the burner is operating under hot water thermostat control, as already described, and that a demand for room heating occurs, causing the room thermostat switch 129 to engage the contacts 130 and 131, a circuit will be closed to relay coil 134, as follows—from secondary 80, by wire 116, terminal 117, wire 132, contact 130, blade 129, contact 131, wire 133, terminal 120, wires 119 and 135, coil 134, wire 92, closed switch 85 and wire 91 to the secondary 80. The relay 134 will be energized and move switches

101 and 109 away from contacts 102 and 110 respectively to disconnect the hot water thermostat 123 from the burner circuit and cause such switches to engage their respective contacts 103 and 111 to connect the room thermostat switch 129 into the burner circuit. The interruption of the circuit to relay coil 64, caused by the movement of each of the switches 101 and 109 from one contact to the other, is of course so short as not to cause opening of any of the switches controlled by the relay, nor will there be time for the stack thermostat to cool sufficiently to open the contacts 90.

If the call for heat originates with the room thermostat 129, the relay 134 will be energized as just above described, and the switches 101 and 109 will be moved to engage their respective contacts 103 and 111. A starting circuit to the relay 64 will be closed, which extends from the secondary 88, by wire 116, terminal 117, wire 132, contact 130, blade 129, contact 131, wire 133, terminal 129, wires 119 and 118, contact 103, switch 101, wire 100 and thence as before traced in connection with the hot water thermostat control. If combustion occurs, the running circuit is established, as before described, by shunting out the heating coil 86. If combustion does not occur, the coil 86 opens switch 85 and stops the burner, as before described. Near the end of the run of the burner, under room thermostat control, blade 129 disengages from contact 131 and allows current to flow through the heater 107. Current now flows from blade 129, by wire 131', heating coil 132', wire 133', terminal 122, wire 121, to contact 111, switch 109, wire 108, coil 107, wire 106, closed switch 83, and conductor 84 to closed switch 81. The heating coil 132' heats up blade 129 and causes it to disengage from contact 130 at an earlier time than it otherwise would. This breaks the circuit to relay 64, causing switches 81, 82, 83 and 63 to open to stop the burner, and breaking the circuit to relay 134, causing switches 101 and 109 to resume their illustrated positions.

The arrangement, as thus far described, is capable of general use with any electrically-operated burner for room heating and hot water heating. The burner, to be controlled by the described arrangement, need not necessarily have two nozzles as shown. However, the arrangement is particularly desirable in connection with a burner having relatively low and relatively high firing rates. It is, for example, desirable and more efficient to operate the burner at the low firing rate than at the high rate, when the burner is being operated for the purpose of heating hot water, and as another feature of the control system, there is provided an arrangement whereby the burner, when controlled by the hot water thermostat, will always operate at the low firing rate. For this purpose there is provided an energizing circuit for the solenoid 48, which controls the flow to the low rate nozzle 7, and a control switch 136 for this circuit, which is normally closed and opens only when the room thermostat switch 129 controls the burner. The blade of switch 136 is connected by a wire 137 to the blade of motor switch 63. Switch 136 engages a contact 138, when relay coil 134 is de-energized. This contact 138 is connected by wires 139 and 140 to a switch 141, which engages a contact 142, connected by wires 143 and 144 to a terminal 145. The latter is connected by a wire 146 to one terminal of solenoid 48. The other terminal of the latter is connected by wires 75

147 and 148 to wire 71. Thus, when the hot water thermostat 123 closes on a demand for heating hot water, the relay 64 is energized, as before described, to close switch 63 and start the motor 6 and energize the primary 62 of the ignition transformer. The closing of switch 63 will close an energizing circuit to solenoid 48, as follows—from terminal 65, by wire 72, closed switch 63, wire 137, switch 136, contact 138, wires 139 and 140, switch 141, contact 142, wires 143 and 144, terminal 145, wire 146, solenoid 48, wires 147 and 148 to wire 71 and up wire 71 to terminal 66. The solenoid 48 will thus be energized to cause the low rate nozzle 7 to be connected to the oil pump. As long as the hot water thermostat switch 123 is in control of the burner, the described energizing circuit will be closed, whenever the motor switch 63 is closed, and low firing rate operation will result. However, whenever the room thermostat switch 129 closes, the relay coil 134 will be energized and switch 136 will be moved away from contact 138 to break the described energizing circuit and to engage another contact 149 to establish another energizing circuit to the solenoid 48 or 55, as selected by other controls to be described.

One of these controls consists of a firing rate selector switch, herein shown as a pivoted tube 150, having a pair of terminals 151 and 152 near one end of the tube and a pair of terminals 153 and 154 near the other end of the tube. One pair or the other of these terminals is adapted to be connected by mercury 155 in the tube, according to the position to which the tube is tilted. The tube may be moved from one position to another either manually or automatically as desired. It may for example, be actuated by a thermostat, such as an outdoor thermostat, conventionally indicated at 150'. The terminals 151 and 154 are interconnected, forming a single supply terminal for the switch, which supply terminal is connected to a supply wire 156. The terminals 152 and 153 are output terminals and are adapted to be connected to the solenoids 48 and 55, respectively. The terminal 152 is connected by a wire 157 to a terminal 158 of the main control instrument and such terminal is connected by a wire 159 to the described wire 140. The output terminal 153 is connected by a wire 160 to a terminal 161 of the main control instrument and such terminal is connected by a wire 162 to a switch 163, engaging a contact 164, which is connected by a wire 165 to a terminal 166. The latter is connected by a wire 167 to one terminal of solenoid 55, the other terminal of which is connected to the described wire 148. The supply wire 156 of the selector switch is connected to the contact 149 of switch 136. As shown, this connection is made through another mercury tube switch, which may optionally be used to secure certain advantages later to be described. Such switch consists of a tube 168, closed at both ends and containing mercury 169, which is adapted to connect one or the other of two pairs of contacts, arranged one pair near each end of the tube. The latter is pivoted and can move from the position shown, in which an output terminal 170 is connected by the mercury 169 to a supply terminal 171, to another position in which the mercury connects a supply terminal 172 to another output terminal 173, which is connected to the supply wire 156 of the selector switch. The supply terminals 171 and 172 are connected together and these interconnected terminals are connected by a wire 174 to a terminal 175 of

the control instrument. The terminal 175 is connected by a wire 176 to the contact 149 of switch 136. Thus, when the tube 168 is tilted to its last-named position, the supply terminal of the selector switch will be connected to contact 149 and, if the latter is engaged by switch 139, to the motor switch 63. And if the tube 168 is not used, the wires 174 and 156 will be permanently connected, as shown in Fig. 7.

Assuming that these wires 174 and 156 are connected by the mercury 169, and that the selector switch is positioned as shown for low firing rate operation, on a call for heat by the room thermostat switch 129, switch 136 will be moved by electromagnet 134 to engage contact 149 and switch 63 will be closed by the electromagnet 64, as already described, and a circuit will be closed to energize solenoid 48 and cause the nozzle 7 to be connected to the oil pump. This circuit may be traced as follows—from terminal 65, by wire 72, closed switch 63, wire 137, switch 136, contact 149, wire 176, terminal 175, wire 174, terminal 172, mercury 169, terminal 173, wire 156, terminal 151, mercury 155, terminal 152, wire 157, terminal 158, wires 159 and 140, switch 141, contact 142, wires 143 and 144, terminal 145, wire 146, solenoid 48, wires 147 and 148 to wire 71, and up wire 71 to terminal 66.

Assuming now that the selector switch is positioned for high firing rate operation the terminals 153 and 154 will be connected by the mercury 155 and a circuit will be closed to energize solenoid 55. This circuit is the same as that just described up through wire 156 and then extends as follows—terminal 154, mercury 155, terminal 153, wire 160, terminal 161, wire 162, switch 163, contact 164, wire 165, terminal 166, wire 167, solenoid 55, wire 148 to wire 71 and up wire 71 to terminal 6. The solenoid 55 may thus be energized to cause the high rate nozzle 8 to be connected to the oil pump.

The switch, involving tube 168, is used where it is desired to secure rapid firing during the initial part of each run of the burner. This switch is actuated by a thermostat 168', which may be responsive to temperature of the steam in the end of the steam main, supplied by the boiler, heated by the burner described. Or the thermostat may respond to the temperature in the return line of a hot water boiler. The switch will be positioned as shown, when the burner starts and will be moved to its other position only after the temperature at the selected location has risen to a predetermined value. When this thermostat switch is positioned as shown, the solenoid 55 will be energized when the burner starts, through the following circuit—from terminal 65, by wire 72, closed switch 63, wire 137, switch 136, contact 149, wire 176, terminal 175, wire 174, terminal 171, mercury 169, terminal 170, a wire 177, which connects the output terminal 170 to terminal 161, terminal 161, wire 162, switch 163, contact 164, wire 165, terminal 166, wire 167, solenoid 55, wire 148, to wire 71, and up wire 71 to terminal 66. Thus, the solenoid 55 will be energized to cause the high firing rate nozzle to be connected to the oil pump. The burner will operate at the high rate until the mains are filled with steam or hot water, as the case may be, when the thermostat responding to a predetermined temperature of the steam or water, as the case may be, will move tube 168 to its other position, breaking the described circuit to solenoid 55 and connecting supply wires 174 and 156 so that the selector switch now becomes operative,

whereupon the burner will continue to operate but at whatever rate is selected by the selector switch.

It may be desirable in a burner of this type, which operates at different firing rates, to periodically purge the nozzle, which is not selected for operation, of the oil therein, which has become heated by the operation of the other and selected nozzle. For example, if the selector switch is set for low firing rate operation, then near the end of each run of the burner, the high rate nozzle will be operated for a brief period to purge it of hot oil. And if the selector switch is set for high firing rate operation, then near the end of each run of the burner, the low rate nozzle, will be operated for a brief period to clear it of the heated oil therein. This is effected by the described switches 141 and 163, which are reversing switches. When switch 141 is moved away from contact 142 it engages a contact 178, which is connected to the contact 164 of switch 163. And when switch 163 moves away from contact 164 it engages a contact 179 which is connected by a wire 180 to wire 143 and thus to the contact 142 of switch 141.

Assuming that the switches 141 and 163 have been moved to engage contacts 178 and 179, respectively, while the selector switch is set as shown for low firing rate operation, the current flow to solenoid 48 will be cut off and directed to solenoid 55 instead. The circuit will be the same as for low firing rate operation, under control of the room thermostat switch, up to switch 141 and then it extends through contact 178, wire 165, terminal 166 and wire 167 to solenoid 55 and thence by wire 148 to wire 71 and up wire 71 to the other supply terminal 66. If the selector switch is set for high firing operation to energize solenoid 55, then, when switches 141 and 163 move to engage contacts 178 and 179 respectively, the solenoid 48, which causes low firing rate operation will be energized. The energizing circuit will be the same as for high firing rate operation under room thermostat control from terminal 65 up to the switch 163 and then will extend through contact 179, wires 180 and 144, terminal 145, wire 146, solenoid 48, wires 147 and 148 to wire 71 and up wire 71 to the other supply terminal 66.

The switches 141 and 163 are simultaneously moved by an electromagnet 181—being positioned as shown when the electromagnet is not energized and moving into engagement with the contacts 178 and 179, respectively, when the electromagnet 181 is energized. This electromagnet is controlled by a thermostat switch 182, normally open but movable to closed position after it has been heated for a predetermined time by the described electric heating coil 107. Switch 182 controls a high voltage circuit for energizing electromagnet 181. The blade of switch 182 is connected by a wire 183 to terminal 69. The contact of switch 182 is connected by a wire 184 to one terminal of electromagnet 181, while the other terminal of the latter is connected by a wire 185 to wire 79 and thus to terminal 66. When switch 182 closes, the electromagnet will be energized through the following circuit—from one supply terminal 65 by wire 72, closed switch 63, wire 73, terminal 69, wire 183, closed switch 182, wire 184, electromagnet 181, wire 185 to wire 79, down wire 79 and across to the other supply terminal 66. Thus, the relay 181 will be actuated to move switches 141 and 163 to reverse the connections to the solenoids 48 and 55 to energize

the one which previously had been deenergized and vice versa.

It will be recalled that heater 107 is energized only after the room thermostat switch 129 has moved away from its contact 131 or after the hot water thermostat switch 123 has moved away from this contact 125, according to which switch is controlling the burner. Thus, the purging of the unselected nozzle will occur at the end of each run of the burner just prior to stopping the burner. The time interval, between the disengagement of blade 129 from contact 131 and its disengagement from contact 130 and the time interval, between the disengagement of blade 123 from contact 125 and its disengagement from contact 124, will not necessarily be equal. For present purposes, this time interval may be assumed to be at least two minutes. Of this time, one minute may be consumed in heating up switch 182 to close it and the balance for the purging of the unselected nozzle.

It may be desirable that the current flow through the heating coil 107 should be substantially the same whether the burner is operating under the control of the room thermostat or under the control of the hot water thermostat. This will insure closure of switch 182 in about the same time in each case. It will be noted that, when the room thermostat controls, the two relay coils 64 and 134 are connected in circuit in parallel. However, when the hot water thermostat controls, the relay 64 is energized, but the relay 134 is deenergized. I provide a coil 205, having the same impedance as relay 134, and connect it by wires 206 and 207 to wires 92 and 104, respectively. When the hot water thermostat controls, the coil 206 will be connected in parallel with relay 64 and take the place of relay 134. Also, when the room thermostat controls, the circuit includes in series the usual anticipating heater 132', while the hot water thermostat has no such heater. To compensate for this, the resistor 113 of the same value as resistor 132' may be added in series to the hot water thermostat circuit. Thus, the same current flow through coil 107 may be secured whether the room thermostat or the hot water thermostat is in control of the circuit.

In Fig. 4, a single solenoid 184' controls a three way valve 185' which is operable to connect the oil supply pipe 61 either to a pipe 186, leading to the low firing rate nozzle 7, or to a pipe 187, leading to the high firing rate nozzle 8. A spring 188 normally holds valve 185' in position for oil to flow to nozzle 8 but, when the solenoid 184' is energized, valve 185' is lifted to close the outlet to pipe 187 and open the outlet to pipe 186 and the nozzle 7. The valve 185' is located within a non-magnetic tube 189. The air-shutter-operating cylinder 32 is controlled by a second valve 190, moved in one direction by a spring 191 and in the other direction by a solenoid 192, when the latter is energized. The valve slides in a non-magnetic tube 193. The inner end of cylinder 32 is connected by a pipe 194 to the space within tube 193. A pipe 195 connects the lower end of the tube 193 to the space within tube 189 and thus to the oil supply pipe 61. The upper end of tube 193 is connected to the described suction pipe 59. When solenoid 192 is not energized, valve 190 prevents flow of oil to cylinder 32 and opens pipe 50 to allow pipe 194 and thus cylinder 32, to communicate with the suction side of the pump. When solenoid 192 is energized, valve 190 is lifted to allow oil to flow through pipe 194 to

cylinder 32 to move the air shutter to low firing rate position and to close the connection to pipe 50. Both solenoids 184' and 192 will be energized simultaneously to secure low firing rate operation. High firing rate operation is secured, when both these solenoids are deenergized.

Substantially the same control system may be used to control the solenoids 184' and 192, except that many connections can be omitted, because 10 neither solenoid is energized for high firing rate operation. Fig. 5 shows the circuits necessary to the operation of these solenoids. The other circuits for controlling the relay coils 64, 134 and 181 by the hot water thermostat and thermostat 15 switches are the same as in Fig. 3. It will be noted, however, that the solenoids 184' and 192 are connected in parallel by two wires 196 and 197, the former being connected to terminal 145 and the latter to wire 71. The wires 165 and 167, 20 terminal 166, wire 177, and the terminals 170 and 171 of the thermostat switch 168 of Fig. 3 are omitted.

Assuming that the hot water thermostat 123 calls for heat, the switch 63 will be closed as before by relay 64 but the switch 136 will remain in engagement with contact 138 because relay 134 is not energized. Also, the switches 141 and 163 will engage their respective contacts 142 and 164 because relay 181 is not energized. A 25 circuit will be established, on closing of switch 63, to energize both solenoids 184' and 192 to secure operation of the burner at the low firing rate. This circuit may be traced as follows—from terminal 65 by wire 72, closed switch 63, wire 137, switch 136, contact 138, wires 139 and 140, switch 141, contact 142, wires 143 and 144, terminal 145, wire 196, solenoids 184' and 192, wire 197 to wire 71 and up wire 71 to terminal 66. Near the end of the run of the burner, the 30 relay 181 will be actuated, as before, to simultaneously move switches 141 and 163 into engagement with their respective contacts 178 and 179, with the result that the burner will operate at the high firing rate because the described 35 circuit for the solenoids 184' and 192 is broken by the disengagement of switch 141 from contact 142. The engagement of switch 141 with contact 178 accomplishes nothing because there is no 40 wire connecting with this contact. The engagement of switch 163 with contact 179 does not accomplish anything because switch 163 has its 45 source of power broken at the switch 150. At the end of the purge run, the hot water thermostat 123 opens, causing relays 64 and 181 to drop out, opening switch 63 to stop the burner and moving 50 switches 141 and 163 back to their illustrated 55 positions.

Assuming now that the room thermostat 129 calls for heat, and that the switches 150 and 168 are in the position shown, the relay 134 will be energized to move switch 136 to contact 149 and then the relay 64 will be energized to close switch 63. The burner motor will start but the solenoids 184' and 192 will not be energized. Starting from 60 terminal 65 as before and passing through wire 72, closed switch 63, wire 137, switch 136, contact 149, wire 176, terminal 175, and wire 174 there is a break between the terminals 172 and 173 of thermostat switch 168. Consequently the 65 burner operates at the high firing rate. Such operation will continue until the thermostat switch 168 moves to its other position to cause the mercury 169 to connect the terminals 172 and 173. Then the burner will operate at the high 70 rate, whichever is determined by the se-

lector switch 150. As shown, this switch is set for the low firing rate and both solenoids will be energized. The circuit is the same as before traced to terminal 172 and then extends through mercury 169, terminal 173, wire 158, terminal 151, mercury 155, terminal 152, wire 157, terminal 153, wires 159 and 140, switch 141, contact 142, wires 143 and 144, terminal 145, wire 196, solenoids 184' and 192, wire 197 to wire 71, and up wire 71 to terminal 66. If the burner continues to operate at the low rate until the demand for heat is nearly satisfied, an automatic switch to high rate operation will occur, when relay 181 is energized by the thermostat 129 disengaging from contact 131. The switches 141 and 163 will be moved to engage their respective contacts 178 and 179 and the last described circuit to the solenoids 184' and 192 will be broken by the disengagement of switch 141 from contact 142.

Assuming now that the selector switch 150 is set for high firing rate operation and that the thermostat switch 168, after being satisfied, moves to cause the mercury 169 to connect the terminals 172 and 173, no circuit will be established to the solenoids 184' and 192 and thus high firing rate operation will continue. If one follows along from wire 174, through terminal 172, mercury 169, terminal 173, wire 156, terminal 154, mercury 155, terminal 153, wire 160, terminal 161, wire 162, to switch 163, there is a break in the circuit to the solenoids because the contact 164, which is then engaged by this switch, has no connection leading therefrom. However, when the relay 181 is energized near the end of the high fire run, as before described, the switch 163 will be moved to engage contact 173 and complete a circuit by wires 135 and 146, terminal 145, wire 196, solenoids 184' and 192, wire 197 to wire 71 and up wire 71 to terminal 66. Thus, the solenoids will be energized to produce a short low firing rate run for purging the nozzle 7.

When the burner is used with a warm air furnace and it is desired to use a fan for circulating the warm air, when the burner is operating under the control of the room thermostat 129, the motor for such fan, designated 198 in Fig. 3, may have one of its terminals connected to a contact 199 of switch 136 by a wire 200, terminal 201 and a wire 202 and its other terminal connected by a wire 203 to wire 71. When room thermostat 129 closes, relay 134 is energized as before described and this will cause switch 136 to engage contact 199, whereby a circuit will be closed to motor 198 as follows—from terminal 65, wire 72, closed switch 63, wire 137, switch 136, contact 199, wire 200, terminal 201, wire 202, motor 198, wire 203, and wire 71 to terminal 66.

In the event that the feature of purging the unselected nozzle near the end of each run of the burner is not desired, the switches 141 and 163, with their actuating relay 181 and the relay control switch 182, with its heating coil 107 and the resistors 101' and 113 may be omitted, together with the wires 111', 140, 143, 144, 162, 165 and 180. The arrangement is shown in Fig. 6. The wires 106 and 108 will be connected and the wires 112 and 114 will be connected. The wires 139 and 157 will extend directly to the terminal 145 and thus to the low firing rate solenoid 48, while wires 160 and 177 will extend directly to the terminal 166 and thus to the high firing rate solenoid 55. The other circuits are the same as in Fig. 3.

Assuming that the hot water thermostat 123

75

calls for heat, the relay 64 is energized as before to close switch 63 and switch 136 remains engaged with contact 138 because relay 134 is not energized. The burner will operate only at the low firing rate as is desired through the following circuit—from terminal 65, wire 72, closed switch 63, wire 137, switch 136, contact 138, wire 139, terminal 145, wire 146, solenoid 48, wires 147 and 148 to wire 71 and up wire 71 to terminal 66. The circuit to solenoid 55 by way of wire 157, terminal 152, mercury 155, terminal 151, wire 156, and terminal 173, is broken by the gap between the terminals 173 and 172. In the event that switch 168 is in the "hot" position so that terminals 172 and 173 are connected by the mercury 169, the circuit will extend by wire 174, terminal 175, wire 176, to contact 149, where there is a break because the switch 136 is disengaged. If the selector switch should be in the high firing rate position, the circuit to solenoid 55 would be broken by the gap between the terminals 152 and 151.

Assuming now that the room thermostat 129 calls for heat and that switch 168 is in the position shown, then the relay 134 will be energized to move switch 136 into engagement with contact 149 and the initial operation of the burner will always occur at the high firing rate regardless of the rate for which the selector switch 150 is set. The circuit is as follows—from terminal 65 by wire 72, closed switch 63, wire 137, switch 136, contact 149, wire 176, terminal 175, wire 174, terminal 171, mercury 169, terminal 170, wire 177, terminal 166, wire 167, solenoid 55, wire 148 to wire 71, and up wire 71 to terminal 66. When the thermostat switch 168 moves to its other position, the described circuit will be broken by the gap between the terminals 170 and 171 but the terminals 172 and 173 will be connected by the mercury 169 and the circuit now extends by wire 156, terminal 151, mercury 155, terminal 152, wire 157, terminal 145, wire 146, solenoid 48, wires 147 and 148 to wire 71, and up wire 71 to terminal 66. Thus, the low firing rate solenoid 48 will be energized. However, if the selector switch 150 were set for the high firing rate, the solenoid 55 would be energized to continue the high firing rate operation through a circuit which is the same as last described, through wire 156 and then extends through terminal 154, mercury 155, terminal 153, wire 160, terminal 166, wire 167, solenoid 55, wire 148 to wire 71, and up wire 71 to terminal 66.

When the control is used for a burner having the high and low firing rate nozzles firing into separate combustion chambers, the surface thermostat switch 168 and the selector switch 150 may be omitted, together with the wires 167, 160, 174 and 177. The arrangement can be that of Fig. 6 with the described switches and wires omitted and the terminal 175 connected to the terminal 166 by a wire 201, as indicated in Fig. 8. With this modified arrangement, whenever the hot water thermostat switch 123 calls for heat the solenoid 48, controlling low rate nozzle 7, will be energized by way of switch 136, contact 138, wire 139, terminal 145, and wire 146, and whenever the room thermostat switch 129 calls for heat the solenoid 55, controlling the high rate nozzle 8, will be energized by way of switch 136, contact 149, wire 176, terminal 175, wire 201, terminal 166 and wire 167.

Whenever the hot water thermostat control

is not desired, the switch 123 and the wires 126, 127 and 128 may be omitted.

It will thus be seen that the invention provides a system for controlling the operation of an electrically operated burner, especially a burner having two firing rates, which system is flexible to meet the various conditions encountered. When a steam boiler or hot water boiler is used for room heating, the invention provides for automatic initially-accelerated firing to fill the mains with steam or hot water, as the case may be, after which the burner will operate at a low or a high firing rate according to the need, as manifested by the selector switch, which may be set manually or automatically for the firing rate best suited for prevailing weather conditions. Regardless of the firing rate for which the selector switch is set, the burner, when controlled by the room thermostat, will always start up at the high rate and the control by the selector switch will be postponed until the mains have been filled with steam or hot water, as the case may be. When the boiler is also used for heating the domestic hot water supply, as by circulating the boiler water through an indirect heater, the control system enables the burner to always operate at the low rate, when controlled by the hot water thermostat. If a call for room heating occurs, before the hot water thermostat is satisfied, the room thermostat will dominate the hot water thermostat and control the burner until the need for room heating is satisfied. The control can also be used for a dual firing rate burner, which fires a warm air furnace, by eliminating the surface thermostat used with steam and hot water boilers to secure initial fast firing, and the hot water thermostat used for control of the burner when heating a domestic supply of hot water. The control can also be used for a burner, having two nozzles located in different combustion chambers which have outlets into a common stack in which the stack thermostat 87 is located. In this case, the surface thermostat switch 168 and selector switch 150 can be dispensed with. The low rate nozzle can fire into the combustion chamber of a hot water heater and the high rate nozzle can fire into the combustion chamber of a warm air furnace. The invention also provides, as a desirable adjunct, an automatic means for purging the unselected nozzle of a dual firing rate burner, where both nozzles are used to fire into the same combustion chamber. If the two nozzles fire into different combustion chambers, obviously the purging feature will not be needed.

The invention thus provides a control system for an electrically operated burner used for house heating service, which provides for room thermostat or hot water thermostat control, with preference to the room thermostat; low rate operation for hot water heating; initial high rate firing for the burner, when used with steam or hot water boilers; high or low rate burner operation for space heating to meet the prevailing weather conditions; and automatic purging of the unselected nozzle when required.

What I claim is:

1. An electrical control system for a dual-firing-rate boiler-firing oil burner of the type wherein a fan and pump, driven by an electric motor under the control of a room thermostat switch, respectively supply air and oil for combustion and electromagnetically-operated valve means are provided to vary the rates of air and

oil supply from those adapted for the relatively low firing rate to those adapted for the relatively high firing rate and vice versa; a control circuit for said means, a selector switch in said circuit movable from one position to another to control said means to effect low or high firing rate operation, a second switch in series with said selector switch in said control circuit and operable to open and close said circuit thereby respectively rendering said selector switch operable and inoperable to control said means and operable when opening said circuit to control said means to effect high firing rate operation, and a thermostat for actuating the second switch and maintaining it open until the temperature at the last mentioned thermostat exceeds a predetermined value.

2. An electrical control system for a dual-firing-rate boiler-firing oil burner of the type wherein a fan and pump, driven by an electric motor under the control of a room thermostat switch, respectively supply air and oil for combustion and electromagnetically-operated valve means are provided to vary the rates of air and oil supply from those adapted for the relatively low firing rate to those adapted for the relatively high firing rate and vice versa; a control circuit for said means, a selector switch in said circuit movable from one position to another to control said means to effect low or high firing rate operation, a second switch in series with said selector switch in said control circuit and operable to open and close said circuit thereby respectively rendering said selector switch operable and inoperable to control said means, a second circuit for controlling said means and operable when closed to actuate said means for high firing rate operation, a third switch connected to move with the second switch and operable to close and open the second circuit when the second switch is moved to open and close the first circuit, and a thermostat for actuating said second and third switches to open the first circuit and close the second circuit until the temperature at the last mentioned thermostat exceeds a predetermined value, whereby operation of the burner at the high rate is had independently of the rate for which the selector switch is set until the temperature at the said last mentioned thermostat exceeds said value.

3. An electrical control system for a dual-firing-rate boiler-firing oil burner of the type wherein a fan and pump, driven by an electric motor under the control of a room thermostat switch, respectively supply air and oil for combustion and electromagnetically-operated valve means are provided to vary the rates of air and oil supply from those adapted for the relatively low firing rate to those adapted for the relatively high firing rate and vice versa; said means including a first electromagnet operable, when energized, to effect high rate firing, and a second electromagnet operable, when energized, to effect low rate firing; a second switch, a thermostat for actuating the second switch, the latter having a supply terminal and two output terminals and movable from a "cold" position, in which one output terminal is connected to the supply terminal and the other output terminal is disconnected from the supply terminal, to a "hot" position in which the supply terminal is disconnected from the first terminal and connected to the other terminal; a selector switch, having a supply terminal connected to the second output terminal of the second thermostat switch and two output terminals connected one

to the first electromagnet and the other to the second electromagnet and movable from one position, in which one output terminal is connected to its supply terminal and the other output terminal is disconnected therefrom, to a second position, in which the supply terminal is disconnected from the first-named output terminal and connected to the other output terminal; and supply wires connected one to the supply terminal of the first thermostat switch and the other to the other terminal of both electromagnets, whereby on a call for heat by the first thermostat switch the burner will operate at the high rate under the control of the second switch until the temperature at the second thermostat rises 15 to a predetermined value.
